UNITED STATES PATENT OFFICE.

GEORGE W. BLACKBURN, OF SARASOTA, FLORIDA.

FISH-LURE.

1,197,334.

Specification of Letters Patent. Patented Sept. 5, 1916.

Application filed August 18, 1915. Serial No. 46,091.

To all whom it may concern:

Be it known that I, GEORGE W. BLACKBURN, a citizen of the United States, and a resident of Sarasota, in the county of Manatee and State of Florida, have invented a new and Improved Fish-Lure, of which the following is a full, clear, and exact description.

My invention relates to means for attracting fish, particularly tarpon.

The object of the invention is to provide a simple and inexpensive contrivance which when in water has a tendency to wobble and produce the effect of a wounded minnow.

The invention is characterized by the provision of an elongated, spoon-shaped member having an aperture adjacent one end and to one side thereof, with a fish-hook associated with the spoon and adapted to cause the same to wobble in the water.

With the above and other objects in view, the nature of which will more fully appear as the description proceeds, the invention consists in the novel construction, combination and arrangement of parts as herein fully described, illustrated and claimed.

In the accompanying drawings, forming part of the application, similar characters of reference indicate corresponding parts in all the views.

Figure 1 is a longitudinal section through the contrivance; Fig. 2 is an under-side view thereof; and Fig. 3 is a cross section on line 3—3, Fig. 1.

Referring to the drawings, 4 represents an elongated, concavo-convex disk the ends of which are rounded, making the disk spoon shape, the convex surface of the disk or spoon forming the top. An opening 5 is provided adjacent one end of the spoon and in alinement with the longitudinal axis thereof through which the shank 6 of a fish-hook 7 projects to engage the under side of the disk and to which it is secured by rivets 8. The hook 7 is disposed below the top of the spoon toward one end thereof and so that the plane of the hook passes through the longitudinal axis of the spoon and is normal to the spoon. The extremity of the hook is preferably in close proximity to the

end of the spoon where the shank of the hook projects through. A swivel 9 is secured to the other end of the spoon 4 to be disposed in alinement with the longitudinal axis. The spoon 4 has also an opening 10 adjacent the end where the swivel is provided. This opening 10 is disposed to one side of the longitudinal axis. When the contrivance is in the water the hook causes the spoon to wobble on the swivel, causing the elongated disk in its wabbling to appear as a wounded minnow, due to the fact that the opening 10 seems like an eye which opens and closes, due to change of positions of the contrivance, thus forming an attraction for the tarpon which causes them to swallow the hook attached to the spoon. Secured to the under side of the spoon and coöperating with the extremity of the hook is a resilient member 11 which prevents weeds from engaging the extremity of the hook and constituting a weedless attachment for the contrivance which renders the device more efficient.

I claim:

In a device of the class described, an elongated spoon having rounded ends and an opening at one end thereof, a hook having a shank projecting through the opening and engaging the concave surface of the spoon, means securing the shank to the spoon in the longitudinal axis of the spoon with the hook depending below the concave surface of the spoon and in a plane passing through the longitudinal axis of the spoon and substantially perpendicular thereto, a swivel at the other end of the spoon, said spoon having an opening to one side of its longitudinal axis adjacent the end where the swivel is provided, and a resilient member from the spoon to the extremity of the hook, said extremity of the hook and resilient member having a gap therebetween.

In testimony whereof I have signed my name to this specification in the presence of two subscribing witnesses.

GEORGE W. BLACKBURN.
